ATTORNEY

UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING FOR RAILWAY-CARS.

1,290,312.

Specification of Letters Patent. Patented Jan. 7, 1919.

Application filed March 23, 1917. Serial No. 156,920.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

My invention relates to improvements in side bearings for railway cars.

One of the objects of my invention is to provide a rocker side bearing adapted to laterally oscillate to accommodate the face of the rocker to the opposed bearing plate. Other objects of my invention will appear from the following description.

20 In the drawings forming a part of this specification, Figure 1 is a side elevation of a side bearing embodying my invention; Fig. 2 is an end view thereof; and Fig. 3 is a cross section taken on line 3—3 of Fig. 1.

25 In the drawings, the numeral 10 indicates a bolster, as, for instance, the truck bolster, to which the base member 11 is secured. The said base member is provided with securing means, as, for instance, the lugs 12 and the rivets 13. A cradle 14 is mounted within the base member and carries within it a rocker 15. The opposing bearing plate secured to a bolster, as, for instance, a body bolster, is indicated at 16.

30 The base member comprises a bottom bearing plate 17 and side walls 18—18, forming between them a longitudinal opening to receive the cradle 14. The base member is open at its ends, and the side walls

40 18 are suitably curved about a center struck at a point lower than the edges thereof to conform to the curve adjacent the walls 19—19 of a cradle 14. The construction as described is such that the cradle cannot be accidentally displaced from the base member and it may laterally rotate therein. The side walls 19 of the cradle are joined at their bottom by a plate 20, the bottom surface of which, 21, is conformed to the groove 17 longitudinally arranged in the bottom of the base member in order that the cradle may laterally rock upon the member 17.

45 On either side the cradle is provided with a shoulder 22 which is opposed to an under-

55 cut shoulder 23 in the base member. This may serve to limit the lateral rocking of the cradle. A bearing member 24 is provided in the bottom of the cradle, and upon this rests the rocker 15. The rocker is held against accidental displacement from the cradle by means of a pin 25 passed through the aperture 26 provided in the rocker, the said aperture being of a larger diameter than the pin. At its ends the pin extends into a longitudinal groove 27 with which the inner faces of the side walls 19 of the cradle are provided to permit the longitudinal movement of the pin therein on rocking movement of the rocker.

60 In assembling the parts of this structure, the rocker is mounted in the cradle and the pin 25 inserted therein, there being an aperture 28 in one of the cradle walls through which the pin may be inserted. The cradle is then inserted in the base member through 70 one end and is held against longitudinal displacement by the block 29, which is displaceable and is provided with securing means, as, for instance, the rivet 30.

75 In the drawings the parts are shown in 80 their normal position. In Fig. 1, the dotted outline of the rocker shows its position when rocked to one end of the cradle. In Fig. 3, the upper face of the rocker is shown by dotted line in a position that it may assume 85 when the cradle is laterally oscillated in order that the upper face of the rocker may accommodate itself to contact with the opposed bolster bearing plate as the plane of 90 said plate in reference to the plane of the 95 face of the opposed bolster changes in the operation of the car.

I claim:

1. In a side bearing for railway cars, a base member, a rocker supporting cradle 95 mounted therein, the cradle being provided with a base plate having a lateral rocking movement upon the floor of the base member, the base member being provided with sides having a sliding engagement with the 100 sides of the cradle, and a rocker associated with said cradle.

2. In a side bearing for railway cars, in combination, a base member, cradle, and a longitudinally movable rocker mounted in 105 the cradle, the base member having sides and an open end to receive the cradle, the cradle having a lateral rotary movement within

the base member, and having stops therein to engage the base member and limit the rotary movement of the cradle.

3. In a side bearing for railway cars, in combination: a housing member, a cradle having bottom and upstanding spaced side walls, and an anti-friction element mounted in the cradle between said side walls, said housing and cradle having coöperating curved bearing surfaces adapting the cradle to rock laterally, and coöperating means on said cradle and housing arranged to limit said rocking movement of the cradle.

4. In a side bearing, in combination: a housing, a cradle, said cradle and housing having coöperating curved bearing surfaces adapting the cradle to rock laterally, a portion of said cradle surface being disposed at the bottom thereof, and an anti-friction element adapted to roll bodily within said

cradle, said cradle having a bearing surface for said element at the bottom thereof and above said curved portions.

5. In a side bearing, in combination: a retaining casting adapted to be secured to a truck bolster of a car, a rocker supporting member carried by said retaining member, said rocker supporting member and retaining member having coöperating curved bearing surfaces adapting the rocker supporting member to rock laterally, a rocker adapted to roll bodily lengthwise of said rocker supporting member, the latter having an upper horizontal bearing surface for the rocker, and means for limiting the rolling movement of said rocker.

In witness that I claim the foregoing I have hereunto subscribed my name this 20th day of Mar., 1917.

JOHN F. O'CONNOR.
